(57) **CLAIM**

The ornamental design for a utensil, as shown and described.

DESCRIPTION

FIG. 1 is a side perspective view of the utensil according to the present invention.

FIG. 2 is a front perspective view of the utensil as shown in FIG. 1.

FIG. 3 is a front view of the utensil as shown in FIG. 1.

FIG. 4 is a rear view of the utensil as shown in FIG. 1.

FIG. 5 is a left side view of the utensil as shown in FIG. 1. FIG. 6 is a right side view of the utensil as shown in FIG. 1.

FIG. 7 is a top view of the utensil as shown in FIG. 1; and, FIG. 8 is a bottom view of the utensil as shown in FIG. 1. The present design is a utensil as shown and described.
